UNITED STATES PATENT OFFICE

99,966

DESIGN FOR A CLOSURE FOR COLLAPSIBLE TUBES OR THE LIKE

Melville Sahyun, Detroit, Mich.

Application February 16, 1935, Serial No. 55,459

Term of patent 14 years

To all whom it may concern:

Be it known that I, Melville Sahyun, a citizen of the United States, residing at Detroit, Wayne County, in the State of Michigan, have invented a new, original, and ornamental Design for Closure for Collapsible Tubes or the Like, of which the following is a specification, reference being had to the accompanying drawing forming a part thereof.

In the drawing—

Figure 1 is a side elevation showing a closure embodying my new design;

Fig. 2 is a top view thereof showing the same closed;

Fig. 3 is a similar view showing the device partly open; and

Fig. 4 is an end view.

I claim:

The ornamental design for a closure for collapsible tubes or the like, as shown.

MELVILLE SAHYUN.
